UNITED STATES PATENT OFFICE.

PETER S. O'REILLY, OF BROOKLYN, NEW YORK, ASSIGNOR TO NATIONAL SEAL COMPANY, INC., OF BROOKLYN, NEW YORK, A CORPORATION OF NEW YORK.

POURING SPOUT.

Application filed October 8, 1924. Serial No. 742,348.

To all whom it may concern:

Be it known that I, PETER S. O'REILLY, a citizen of the United States, and a resident of the borough of Brooklyn, in the 5 county of Kings, city and State of New York, have invented certain new and useful Improvements in Pouring Spouts, of which the following is a specification, reference being made to the accompanying drawings,

10 forming a part thereof.

My invention relates to spouts for directing the flow from the discharge openings of containers or receptacles, and is particularly adapted for use with the pouring nozzles 15 mounted on sheet-metal cans on which the spout may be partially revolved over the top of the can when not in use.

The objects of my invention are, among other things, to provide a spout of this type 20 stamped to the required size and shape out of a single piece of sheet metal and formed with a pair of resilient locking jaws adapted to engage the periphery of the nozzle and hold the spout in position relatively thereto 25 by the jaws being clamped around the neck of the nozzle; such pouring-spout is particularly adapted for use on nozzles having projections or lugs on the upper portion of the neck which lugs are engaged by in- 30 turned lips from the depending skirt of a screw-cap serving as a closure for the nozzle opening.

A further object is to provide a pouring-spout which may be economically manufactured, readily applied to and removed from the nozzle, and efficient in use while permitting a rotary retracting movement out of the way during shipments or when not in use to pour the liquid from the can.

40 A preferred form of my invention is illustrated in the accompanying drawings in which—

Fig. 1 is a top plan view of the spout;

Fig. 2 is a section on the line 2—2 of 45 Fig. 1; and

Fig. 3 is a vertical section of the spout as applied to the nozzle of a can, the nozzle being shown partly in section with the screw-cap in vertical section.

50 Similar numerals refer to similar parts throughout the several figures.

The top 4 of the sheet-metal can 5 has the nozzle 6 secured thereto, the nozzle opening 7 being closed by the screw-cap 8 with inner liner plate 9 engaging the edges of the

opening 7. The cap-skirt 10 has the in-turned lips 11 to engage and coact with the horizontal lugs 12 formed in the upper portion of the nozzle as shown in Fig. 3 whereby the cap 8 is removably secured to the 60 nozzle 6. These parts may be of the ordinary and approved construction, and do not of themselves constitute an element of my invention.

My improved pouring-spout 13 is preferably formed of a single piece of sheet-metal which is stamped and shaped as shown in Fig. 1 with the depressed body portion 14 and the converging end constituting the pouring lip 15. The larger and opposite 65 end is formed with a pair of oppositely-disposed resilient clamping jaws 16 and 17 having their ends 18 and 19 respectively rounded in any approved manner. The distance between the inner sides of the jaw 70 ends 18 and 19 is slightly less than the outer diameter of the nozzle 6, and the upstanding circular shoulder flange 20 is adapted to bear against and frictionally engage the neck of the nozzle 6 in a surface-to-surface 75 contact when the spout 13 is applied thereto with the spring jaws 16 and 17 clamped about the nozzle neck, all as shown in Fig. 3. This flange 20 is continued around the 80 jaw ends 18 and 19 to form the raised marginal flange along the edges of the spout body 14 tapering toward the pouring lip 15 as shown in Fig. 1.

The spout 13 is applied to the nozzle 6 by forcing the jaws 16 and 17 inwardly 85 against the neck of the nozzle, thereby causing the jaws to expand or spring outwardly and then move inwardly as the spout 13 is locked in snug engagement with the nozzle 6 as shown in Fig. 3. The lugs 12 coacting 90 with the top edge of the flange 20 prevent the spout 13 from being removed upwardly and the spout may be partially revolved around the nozzle 6 in retracted position to extend over the top 4 of the can to avoid 95 injury when not in use, as shown in full lines in Fig. 3, the dotted line position showing the pouring lip 15 beyond the top 4 in proper position for pouring. When positioned as shown by dotted lines, my improved spout 13 effectively directs the flow 100 of liquid from the can 5; it is also evident that such spout may be readily detached by pulling same away from the nozzle 6, and 105 separate spouts may be provided with each 110

can to be thereafter sprung to the nozzle by the user. The tapered form of the pouring lip 15 adapts it for pouring the liquid into the neck opening of a bottle or another can if desired.

It will be seen that my improved pouring-spout may be readily applied to or removed from the nozzle neck by a horizontal "spring-snap" movement irrespective of 10 projecting lugs or screw threads formed about the upper periphery of the nozzle 6 which is an advantageous feature in cans of this type. While I have shown and described a preferred form of my invention, 15 many changes or modifications may be made in the structural parts without departing from the principles of my improvement or sacrificing its advantages.

I claim as my invention:

- 20 1. In combination, a container having a cylindrical nozzle outlet, and a rotatable pouring-spout having a pair of clamping jaws to partially surround and engage the neck of said nozzle outlet by a surface-to-surface contact, with a connecting upstanding shoulder flange lying in substantially the same plane as said spout and said jaws, both jaws and flange forming a continuous co-axial bearing against said neck to hold 25 said spout locked to said nozzle but permitting a rotary movement relatively thereto.
2. In combination, a container having a cylindrical nozzle outlet with spaced-apart cap-engaging lugs on its neck and a rotatable pouring-spout having a pair of oppositely-disposed spring clamping jaws with a connecting upstanding shoulder flange, both jaws and flange co-axially bearing against said neck, said jaws being 30 adapted to snap around and partially surround said nozzle neck but permitting a rotary movement relatively thereto, and said flange coacting with said neck lugs to pre-

vent upward removal of said spout from 45 said nozzle outlet.

3. A pouring-spout to engage can nozzles comprising a body with a pouring lip at one end thereof and a pair of spring clamping jaws and a connecting upstanding circular shoulder flange at the other end adapted to partially surround said nozzle in a surface-to-surface contact and lock said spout thereto, said lip and jaws and shoulder flange lying substantially in the same plane. 50

4. A pouring-spout to engage can nozzles comprising a body with a pouring lip at one end thereof and a pair of spring clamping jaws and a connecting upstanding circular shoulder flange at the other end adapted to partially surround said nozzle in a surface-to-surface contact and removably lock said spout thereto, while permitting a rotary movement about said nozzle, said lip and jaws and shoulder flange lying substantially 55 in the same plane.

5. In combination, a container having a cylindrical nozzle outlet having spaced-apart cap-engaging lugs on its neck, and a rotatable pouring-spout removably applied thereto, said spout comprising a depressed body portion with a pouring lip at one end thereof and a pair of oppositely-disposed spring clamping jaws with a connecting upstanding circular shoulder flange located at the other end, said jaws being adapted to snap around and partially surround said nozzle neck with said shoulder flange in co-axial surface-to-surface engagement therewith to lock said spout to said nozzle, but permitting a rotary movement relatively thereto, the top edge of said shoulder flange coacting with said container lugs to 70 prevent removal of said spout from said nozzle outlet. 75

PETER S. O'REILLY.
